DESIGN FOR A SHOE

Morris Lippert, Brooklyn, N. Y.

Application April 3, 1937, Serial No. 68,544

Term of patent 3½ years

To all whom it may concern:

Be it known that I, Morris Lippert, a citizen of the United States of America, residing in Brooklyn, county of Kings, and State of New York, have invented a new, original, and ornamental Design for a Shoe, of which the following is a specification, reference being had to the accompanying drawing, forming part thereof, wherein,

I claim:

The ornamental design for a shoe, substantially as shown.

MORRIS LIPPERT.
